UNITED STATES PATENT OFFICE.

WILLIAM D. BERRY, OF LOUISVILLE, KENTUCKY.

CATAMENIAL APPLIANCE.

No. 857,019.

Specification of Letters Patent.

Patented June 18, 1907.

Application filed July 22, 1904. Serial No. 217,635.

To all whom it may concern:

Be it known that I, WILLIAM D. BERRY, a citizen of the United States, residing at Louisville, in the county of Jefferson and 5 State of Kentucky, have invented a new and useful Catamenial Appliance, of which the following is a specification.

My invention relates to appliances to be worn during the catamenia, and the objects 10 of my improvement are, comfort, sanitation, durability, safety, economy, and inexpensiveness. These objects I attain by means of the device illustrated in the accompanying drawing in which—

15 Figures 1, 2 and 3 are perspective views, and Fig. 4, a fragmentary plan view of the rear end of the pouch.

Similar reference numerals refer to similar parts throughout the several views of the 20 drawing.

The pouch, 1, and the elastic straps 2 and 3 constitute the body of the invention. The pouch 1 is approximately triangular in shape and made of thin, soft and open meshed material. The edge is bound round with soft, 25 flexible binding or tape to prevent the edge from stretching and curling over and moving out of position, to cause it to fit permanently and accurately in proper position and to 30 serve the pouch form. A strip of tape also extends perpendicularly from the base of the triangle to the apex so as to form a substantial bottom for the pouch and also preserve the pouch form. Each angle is provided 35 with a flexible strap, 4, and to the ends of these straps are secured corresponding parts of the conventional glove fastener, 5. The glove fastener is preferably used because it presents no angles or sharp tongues such as 40 are incident to buckles, pins and the like, and thus renders the pouch comfortable and easily washable. At the apex a broader flexible strap, 5, is used than at the other angles, and two glove fasteners, as shown in Fig. 4. This 45 broad strap forms a guide for the elastic leg strap, 3, and is made of soft flexible material in order that it may be comfortable and not chafe or bruise the nates. The belt, 2, suspends the pouch from the hips. It is made 50 of elastic and formed of two pieces. It does not extend entirely round the body, but a gap is left in front which is occupied by the base of the triangle of the pouch. At one 55 end of each portion 2 of the belt is secured a metal loop, 6, adapted to receive a flexible strap, 4, attached to pouch 1, having an open-

ing or slot sufficiently large to allow the free part of the glove fastener 5 to pass through. At the opposite end of the parts of the belt are secured two-slotted metal loops or sliding buckles which hold simply by friction; and the one portion of the belt slides through the loop or buckle attached to the other portion mutually, so that a portion of the belt at the back is doubled. The object of this arrangement is to render the belt adjustable to fit any sized person and yet avoid leaving loose ends to curl up and get in the way and form uncomfortable lumps. Near the front ends of the belt are secured the ends of the 60 leg strap 3. This strap is made of elastic, preferably narrower than the belt, and one of its ends is sewed or otherwise fixed permanently to the belt; the other end is passed through a metal loop, 10, secured near the 65 opposite end of the belt and secured to the two-slotted metal loop 9, which has previously been strung on the strap. Thus a portion of this end of the leg strap is doubled, and the strap may be readily adjusted in 70 length to fit any sized person by sliding the loop, and no loose end is left to annoy the wearer. By my arrangement for the adjustment of the belt, the distance of the leg strap from the middle of the pouch and the symmetrical arrangement of the parts in front is 75 not disturbed when the belt is adjusted. The pouch is attached to the leg strap by passing the flexible strap 4 on the apex around the leg strap and closing the glove fasteners. 80 The strap 4 is of sufficient length not to bind the leg strap, but allow the parts of the appliance to adjust themselves readily.

The use of the appliance will now be readily understood. To assemble it, the glove 85 fasteners are opened, straps 4 at the base are passed through loops 6 and the glove fasteners closed, strap 4 on the apex is passed around leg strap 3 and the fasteners closed. To put the appliance on, the feet are placed 90 in the belt and the leg strap and astride the pouch, and the appliance is drawn up thus and the belt is stretched over the hips till it rests upon them. The strap 3 will now pass around the nates and the pouch will adjust 95 itself comfortably over the vulva. It will be seen that the belt does not pass around the waist, but rests upon the hips and dips downward in front so as to draw the pouch upward. Any soft, absorbent material may 100 now be placed in the pouch by simply stretching the belt forward, or by sitting down

(Fig. 3) and stripping the leg strap forward on the legs, and the soiled absorbent may in like manner be removed without undoing any fastening or disturbing any adjustment. Absorbent cotton seems to be the preferable material because it is thoroughly absorbent, soft, inexpensive, easily carried about without suspicion or embarrassment, and can be readily disposed of or destroyed when soiled. Fig. 3 shows how the appliance may be drawn forward when the wearer is in a sitting posture, making the normal evacuation of the bowels and the bladder convenient without danger of soiling the appliance and also without disturbing any fastening or adjustment, or danger of soiling the under-wear or the body with the catamenial elimination taken up by the absorbent.

I am aware that pouches of somewhat similar form have been used and made of rubber or other impervious material. Such materials lack ventilation and are uncomfortable and, if any of the catamenial elimination escapes to the outside while the wearer is lying down on the side or in any unusual posture, it cannot be absorbed and consequently causes great discomfort. I therefore make my pouch of open-meshed, soft and absorbent material so that any leakage is at once absorbed therethrough by the absorbent material and all uneasiness and discomfort is avoided. Furthermore, the material of the pouch being soft and flexible, and the absorbent being soft and fluffy, they may be easily compressed where necessary and avoid the bunchiness experienced in the use of cloths. It is obvious that my arrangement of the belt and leg strap obviates any pulling and chafing or danger of the pouch shifting out of proper effective position in whatever posture the body may be.

Having thus described my invention so that its construction and use are obvious, I claim—

1. In a catamenial appliance, the combination of a two-part elastic belt adjustable at the back, each part of said belt having its rear end permanently fastened to a friction-buckle, an elastic leg strap fixed to said belt, and a flexible and absorbent co-cave pouch detachably applied to said belt and said leg strap, substantially as specified.

2. In a catamenial appliance, the combination of an elastic belt around the body and

resting on the hips comprising two equal parts, an elastic leg strap passing around the nates and having its ends fixed to said parts of said belt near the front and at equal distances from the front ends of said parts of said belt, a light, thin absorbent pouch having on two of its angles means for detachably securing to the front ends of said parts of said belt, and on its apex means for detachably applying to said leg strap, and absorbent material placed in said pouch and held gently and yieldingly against the vulva by said elastic belt, said elastic leg strap and said pouch, substantially as specified.

3. In a catamenial appliance, the combination of a belt formed of two equal elastic straps each having at one end permanently attached a loop and at the other end permanently attached a conventional friction-buckle, the friction-buckle on the one strap strung on and adapted for adjustment on the other belt strap mutually forming means for adjusting the length of said belt, a leg strap having one end fixed to the one strap of said belt toward the front end thereof and the other end having a conventional friction-buckle, said leg strap passing slidably through a loop permanently fastened on the other of the belt straps symmetrically with the other end, an absorbent pouch or sack detachably fastened to said belt and said leg strap, and soft, fluffy absorbent material removably placed in said pouch so disposed and arranged as to yieldingly press against and cover the vulva and adjacent parts, substantially as specified.

4. In a catamenial appliance, a supporting belt formed of two straps each of which has permanently fastened at one end a buckle, the buckle on the end of one strap strung on, and adapted to be adjusted on the body of the other strap mutually and held in position by friction and forming means for adjusting the length of said supporting belt, and means for absorbing the catamenial flow comprising a sack composed of absorbent material adapted to absorb any overflow or leakage and loose absorbent material removably placed in said sack, substantially as and for the purpose specified.

WILLIAM D. BERRY.
